(57) **CLAIM**

The ornamental design for an air release valve, as shown and described.

DESCRIPTION

FIG. 1 is a front view of an air release valve showing my design;

FIG. 2 is a rear view thereof;

FIG. 3 is a left-side view thereof;

FIG. 4 is a right side view thereof;

FIG. 5 is a top view thereof;

FIG. 6 is a bottom view thereof; and,

FIG. 7 is an isometric side view thereof.

The broken lines shown in the drawings are directed to environment and form no part of the claimed design.
